United States Patent

Des. 240,837

Patented Aug. 3, 1976

240,837

WALL PLAQUE OR SIMILAR ARTICLE

Doris Sweeney, 512A Taylor Ave., Warrington, Pa.
18976, and Mary Ellen Lee, 7951 Anita Drive, Philadelphia, Pa. 19111

Filed Feb. 7, 1975, Ser. No. 548,025

Term of patent 14 years

Int. Cl. D11—02

U.S. Cl. D29—23 B

FIG. 1

FIG. 2

FIG. 3

FIG. 1 is a front elevational view of a wall plaque or similar article showing our new design.

FIG. 2 is a rear elevational view thereof.

FIG. 3 is a side elevational view thereof.

We claim:

The ornamental design for a wall plaque or similar article, substantially as shown.
